Primary Examiner — Kevin K Rudzinski*Assistant Examiner* — James P McKane(57) **CLAIM**

The ornamental design for a head band, as shown and described.

DESCRIPTION

FIG. 1 is a front, right, and top perspective view of a head band, showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view taken from the encircled portion labeled "9" in FIG. 1.

The short dash long dash broken lines in FIGS. 1 and 9 depict the boundaries of the enlarged area and form no part of the claimed design.

1 Claim, 9 Drawing Sheets(56)
